ADJUSTABLE SHORES

Henry P. Albrecht, Minneapolis, Minn.

Application November 27, 1953, Serial No. 394,574

2 Claims. (Cl. 248—354)

My invention relates to adjustable supporting devices and more particularly to adjustable shores for use in the building industry and for supporting overhead forms for concrete construction.

Such shores are interposed between a floor and the overhead supporting timbers supporting the forms for the immediately overlying floor. Normally such shores include a pair of telescoping column sections which are locked together at a desired height by inserting pins through alignable longitudinally spaced openings therethrough, and an independent screw element. In positioning such shores between the floor and the overlying supporting beams, the column sections are first extended to the point where the openings in the outer section align with the closest opening in the inner section, and a pin is placed through said aligned openings. The fine or vernier adjustment of the sections is taken care of through the medium of the screw element. Frequently a considerable gap remains to be taken up by the screw element and this adjustment is obviously time-consuming and laborious. In fact in operations where large numbers of such shores are utilized, the time and labor involved in achieving such vernier adjustments becomes a considerable expense factor.

The primary object of my invention is the provision of an adjustable shore which may be much more quickly and easily installed in operative position than any shore heretofore produced. To this end I provide novel means for quickly and effectively extending the shore to any operative height with a much greater degree of accuracy than heretofore possible, prior to rotating the screw element for the final or vernier adjustments, whereby to reduce to a minimum the final adjustment to be achieved through the medium of said screw element.

A still further object of my invention is the provision of a device in the class described which has a minimum of working parts, is extremely easy to operate, which is fool-proof in construction and durable in use.

The above and still further objects of my invention will become apparent from the following detailed specification, appended claims and attached drawings.

Referring to the drawings wherein like characters indicate like parts through several views:

Fig. 1 is a view in front elevation of my novel structure;

Fig. 2 is a view in side elevation;

Fig. 3 is a fragmentary view partly in vertical axial section and partly in rear elevation as seen substantially from the line 3—3 of Fig. 2; and

Fig. 4 is a perspective view of the collar of my novel structure.

Referring with greater particularity to the drawings the numeral 1 indicates in its entirety a supporting column comprising a tubular lower section 2 and an upper section 3, shown as telescopically received in the open upper end portion of the section 2. Preferably and as shown, the lower section 2 is provided with an enlarged foot 4 for engagement with the ground or floor A and

2

the upper section 3 is provided at its upper end with an elongated beam supporting saddle 5. A tubular extension element 6 is shown as having screw threaded engagement with the upper end portion of the lower section 2, as indicated at 7. To facilitate rotation of the extension element 6, I provide an inverted U-shaped mounting bracket 8 on the side of the tubular extension element 6 between the sides of which is pivoted, through the medium of a pivot pin 9, a handle 10. Handle 10 is obviously swingable from the inoperative position shown, wherein it is parallel to the axis of the element 6, to a radially projecting operative position, not shown.

Overlying the extension element 6 for independent rotary and axial sliding movements on said upper column section 3 is a collar 11, which, preferably and as shown in Fig. 3, is provided with a reduced end portion 12 freely rotatively received within the socket-forming upper end portion 13 of the extension element 6.

As shown, the intermediate portion of the upper section 3 is provided with a plurality of longitudinally spaced diametrical openings 14 therethrough. Openings 14 may be in vertical alignment, or as shown, may be both circumferentially or longitudinally spaced with respect to each other. The collar 11 is formed to provide a pair of diametrically opposed step-like members 15, each of which provides an arcuate supporting surface 16 for the selective reception of the opposite ends of a pin 17 inserted through a given opening 14 in the upper section 3. Preferably and as shown, the pin 17 is connected at one end to a tie chain 18. The opposite end of chain 18 is in turn preferably connected to an ear 19 projecting laterally outwardly from the side of the collar 11 adjacent the lower end thereof.

Also preferably and as shown, the extension element 6, adjacent its upper end, is provided with a pair of opposed openings 20 which are likewise selectively registerable with the openings 14 and the upper section 3, for a purpose which will hereinafter become apparent.

When it is desired to place my novel shore in operation, the same is placed in a retracted position with the foot 4 on the floor A immediately below a beam, not shown. The column 1 is then extended by telescopically raising the upper section 3 to cause the elongated saddle 5 to receive and engage the said beam. Next the collar 11 is rotated to cause alignment of the closest opening 14 in the upper section 3, with the closest arcuate seats 16 making up the opposed step-like members 15. Next the pin 17 is inserted through the opening 14 with the opposite ends thereof coming to rest in the aligned arcuate seats 16. Lastly, the effective length of the column 1 is arrived at by rotation of the screw threaded extension element 6, after handle 10 has been swung to its radially extended position. However, because of the aligned seats 16 on the opposed step-like members 15, the relatively slow and time-consuming rotation of the extension element 6 is reduced to a minimum.

When it is desired to store or transport my novel shores, the pin 17 is inserted through the aligned openings 20 in the extension element 6, and any one of the longitudinally spaced openings 14 in upper section 3, and the several elements are thereby effectively tied together.

My invention has been thoroughly tested and found to be completely satisfactory for the accomplishment of the above objects and while I have shown a preferred embodiment thereof, as required by section 4888 of the Revised Statutes, I wish it to be understood that my invention is capable of modification without departure from the scope of the appended claims.

What I claim is:

1. An adjustable supporting column comprising a tubular lower section having the upper end thereof open, an upper section having a plurality of longitudinally spaced

diametrical openings therethrough telescopically received in the open upper end portion of said tubular lower section for initial axial extending and retracting movements, an extension element threadably engaged with the upper end portion of said lower section, a collar overlying and engaging said extension element and having independent rotary and axial movement therewith on said upper section, operating means on said extension element for rotating same to provide vernier axial adjustment of said upper section through said collar, said collar having pairs of diametrically opposed longitudinally spaced step-like portions each pair of which provide a supporting surface selectively supporting the ends of a pin inserted through a selected opening in said upper section providing an intermediate axial adjustment of said upper section between said initial and vernier adjustments, aligned diametrical openings in said extension element alignable with a selected opening in the upper section for receiving means to secure the sections together for transportation or storage.

5

2. The structure defined in claim 1 wherein the independent rotary and axial movement of the collar with respect to the extension element is provided by a reduced end portion on said collar nestingly received within a socket defined in the portion of the extension element engaging the collar.
